Primary Examiner — Kevin K Rudzinski*Assistant Examiner* — Amber J Rabie(74) *Attorney, Agent, or Firm* — Baker, Donelson,
Bearman, Caldwell & Berkowitz, P.C.; Edward D.
Lanquist, Jr.; Dominic A. Rota(57) **CLAIM**What is claimed is the ornamental design for an ammo box
filling tool, as shown and described.

DESCRIPTION

FIG. 1 is a top perspective view showing the ammo box
filling tool of Applicants' invention.FIG. 2 is a bottom perspective view of the ammo box filling
tool of FIG. 1.FIG. 3 is a top plan view of the ammo box filling tool of FIG.
1.FIG. 4 is front elevation view of the ammo box filling tool
of FIG. 1, the rear elevation view being an identical mirror
image thereto.FIG. 5 is bottom plan view of the ammo box filling tool of
FIG. 1.FIG. 6 is a left side elevation view of the ammo box filling
tool of FIG. 1; and,FIG. 7 is a right side elevation view of the ammo box filling
tool of FIG. 1.**1 Claim, 3 Drawing Sheets**(56)
